UNITED STATES PATENT OFFICE.

LEO J. ROUSSEAU, OF DETROIT, MICHIGAN.

TOY.

Application filed October 26, 1925. Serial No. 64,738.

This invention relates to toy velocipedes for the use of children, and has for its object to provide a device which is very simple mechanically and therefore easy for a child 5 to operate, and which is of a nature calculated to particularly appeal to children due to its mode of operation and use, and its appearance.

More particularly the invention contemplates the providing of a preferably wheeled base structure with supports extending upwardly therefrom between which is fulcrumed a board adapted to rock and to form a seat at the rear end for the user, 15 whereby such user may bounce vertically on the said seat, downward movement of which is effected against the action of a suitably arranged spring.

The invention still further aims to provide for the utilizing of such motion of the seat to effect the propelling of the device.

Still further objects subsidiary to or resulting from the aforesaid objects, or from the construction or operation of the invention 25 as it may be carried into effect, will become apparent as the said invention is hereinafter further disclosed.

In carrying the invention into effect I may adopt a novel construction and arrangement of parts hereinafter described, 30 having reference to the accompanying drawing, wherein—

Figure 1 is a perspective view of a child's toy embodying my invention;

Figure 2 is a detail cross sectional view 35 illustrating the attachment of the restraining spring to the seat board;

Figure 3 is a fragmentary elevation partly in section illustrating a modification of the invention, and Figure 4 is a transverse section of the same taken on the line 4^x—4^x, 40 Figure 3.

Similar characters of reference indicate 45 similar parts in the several figures of the drawing.

The device includes a preferably wheeled base structure comprising a base board 1 provided with front and rear wheeled transverse members 2 and 3, the first of which 50 is preferably pivotally attached to the base board and the member 3 fixedly attached thereto.

The base board 1 is provided with a pair of upstanding brackets or arms 4 located at 55 some little distance from the forward end of the said base board, the upper ends of

the said arms receiving a transverse rod 5 upon which is mounted a longitudinally extending seat board 6, the rear end of which is shaped to form a seat 7 and the forward end of which extends substantially forward of the said supports 4 and is provided with a longitudinally extending groove 8 in the underside thereof and transverse holes 9 through one or other of which a pin 10 may be passed to effect the securing of the upper end of a spring 11 to the forward end of the said seat board 6. The lower end of the said spring 11 is attached as by means of an eye-bolt 12 to the forward end of the base board 1. 13 are handle bars suitably mounted on the forward end of the seat board 6.

The invention in this form is especially suitable for very small children, as they may when seated upon the seat 7 simply bounce up and down, a motion which is quite easily effected due to the action of the spring 11 and which appeals to very young children but for older children I prefer to provide means whereby this motion may be utilized 75 to effect the propelling of the device. This simply calls for the provision of a cranked axle 14 for the rear wheels, as shown in Figures 3 and 4, the base board 1^a having an opening 15 therein in this case through which opening extends a connecting rod 16 coupling the cranked axle with an eye-bolt or similar device 17 on the underside of the seat 7. It will be quite obvious that the vertical rocking of the seat board 6 may in this 80 case effect the rotation of the rear wheels of the device and its consequent propulsion.

The device is preferably designed to simulate some animal or device, and in the present instance a certain resemblance to a rabbit is given to the toy so that to the childish mind the idea is conveyed that the described motion is similar to that of a running rabbit.

It will also be readily apparent that the 100 point of connection of the upper end of the spring 11 to the board 6 relative to the fulcrum rod 5 may be varied according to the particular orifice 9 through which the pin 10 is passed. Thus increased resistance to the motion of the seat 7 may be offered by simply moving the spring securing pin 10 towards the forward end of the said board 6 and the resistance reduced by moving the pin in the opposite direction.

This invention may be developed within 105 the scope of the following claims without

departing from the essential features of the said invention, and it is desired that the specification and drawing be read as merely illustrative and not in a limiting sense, except as necessitated by the prior art.

What I claim is:—

1. In a device of the class described, a base structure, a seat board elevated above such structure and vertically swingable about a point intermediate of its length, a seat at one end of said board, and a tension spring extending between the base structure and the forward end of said board, against the action of which spring said board may be rocked by a child seated thereon, said spring forming the sole means of yield-
- 10
- 15

ably maintaining said seat in a normally horizontal position whereby said seat board is permitted to extend rearwardly in an unobstructed manner from its fulcrum point.

2. In a device according to claim 1, wherein means are provided for adjusting the resistance offered by said spring to the movement of said board.

25 3. In a device according to claim 1, wherein means are provided for varying the point of attachment of the said spring to said board relative to the fulcrum of said board.

30 In testimony whereof I affix my signature.

LEO J. ROUSSEAU.
